UNITED STATES PATENT OFFICE.

CARL F. ABERLE, OF ST. LOUIS, MISSOURI.

BUILDING CONSTRUCTION.

Application filed March 31, 1924. Serial No. 703,111.

To all whom it may concern:

Be it known that I, CARL F. ABERLE, a citizen of Germany, residing at the city of St. Louis, Missouri, have invented a new and useful Building Construction, of which the following is a specification.

This invention relates to building construction.

An object of the invention is to provide a wall composed of a plurality of specially constructed units arranged to be assembled together, the units having interlocking parts.

Another object of the invention is to provide a wall of the class described so that the assembled units will produce a continuous structure having an inner and outer wall surface with intermediate air passages throughout the length and height of the wall, thereby providing for the elimination of moisture accumulating within the wall structure.

Another object of the invention is to provide a wall composed of a plurality of units so arranged that the units forming the longitudinal length of the wall are of duplicate construction, having special units at the terminals and at the corners only, thereby minimizing the cost of manufacture of the units.

Additional advantages of the invention will be apparent from the detailed description thereof, taken in connection with the accompanying drawing in which

Fig. 1 is a plan view of the wall structure illustrating the assembly of two layers of units.

Fig. 2 is a plan view of a single layer of assembled units.

Fig. 3 is a vertical section taken on the line 3—3 of Fig. 1.

Fig. 4 is an isometric view of a single side wall unit.

The main body of the wall is formed from duplicate units illustrated particularly in Fig. 4, it being understood that this unit is used both for the inner and outer wall on the longitudinal stretches thereof. The unit is formed of any suitable plastic material and includes a wall 1, said wall being provided at its upper portion with a ledge 2. At each end of the wall 1 is a flange 3 extending at right angles from the wall, said flange having a tapering inner surface and a flat end surface. Intermediate the flanges 3 and extending backwardly at right angles from the wall 1 is a flange 4.

The ends of the wall 1 have channels 5 formed therein.

The outer corner unit is formed with angular matching walls 6 and 7, the wall 6 being of a greater length than the wall 7, and the wall 6 having an inwardly extending flange 8 similar to the flanges 4 for the side wall units. The inner corner sections are the same as the side wall sections, with the exception that the wall 1 is not extended for the full length of the side wall unit but is cut off in respect of the corner section 9 at a point just beyond the flange 4 and in respect of the section 10 at a point approximately at the intersection of the inner face of the flange 3 with said wall 1. With the exception of the special terminal units 11 a rectangular wall may be completely constructed by utilizing the small number of units as above described.

In Fig. 1 two courses or layers of the wall structure are illustrated. The shaded portion of the drawing shows the under layer which is isolated and shown alone in Fig. 2. From these views the manner in which the units are laid is clearly apparent. The corner members in each layer are reversed in respect of each other. The side wall units are connected with the corner members in such way that the inner and outer wall units are arranged in staggered relationship. It will be noted that as the side wall units are placed end to end the flat walls of the flanges 3 match each other and form together inwardly extending pedestals, and also that intermediate these pedestals are the pedestals formed by the flanges 4 and 8. As the pedestals thus formed alternate or are in staggered relationship in the inner and outer walls, and also in staggered relationship in the adjacent layers, provision is made for the pedestals overlying each other when the units are assembled. The units are set up in mortar or cement, cement being utilized at all adjacent joints. The wall thus provided has great strength, as it is cross tied through the agency of the matching pedestals in the inner and outer wall of the separate layers, at the same time providing a continuous air passage throughout the length and height of the wall and permitting sufficient air circulation to prevent accumulation of moisture in the wall structure.

It will be noted by reference to Fig. 3 that the ledges 2, which are formed in the

vertical face of all of the units, extend inwardly a slight distance from the plane of the adjacent edge of the matching unit. This provides for the support of the binding material, effecting a better joint between the matched units.

I am aware that the construction may be modified in certain particulars without departing from the spirit and scope thereof.

10 What I claim and desire to secure by Letters Patent is:—

A wall comprising spaced inner and outer wall facings each composed of a series of superimposed blocks breaking joint respectively, abutting projections on the ends of the blocks of each facing extending toward

and terminating out of contact with the surfaces of the opposite blocks of the other facing, a projection on the block of each facing intermediate of said end projections and of equal length terminating out of contact with the inner surfaces of the opposite blocks of the other facing, the end projections of the blocks of each facing bearing vertically upon the intermediate projections of the blocks of the other facing, and vice versa, and ledges along the upper corners of said blocks between said projections of greater thickness than the remaining portion of the blocks.

CARL F. ABERLE.
